by Sam'l C. C. Smith,
his Atty's.

UNITED STATES PATENT OFFICE.

JAMES F. SMITH, OF ST. LOUIS, MISSOURI, ASSIGNOR OF ONE-THIRD TO ANTHONY F. ITTNER AND ONE-THIRD TO ARTHUR H. BRADLEY, BOTH OF ST. LOUIS, MISSOURI.

TALKING MACHINE.

Application filed December 3, 1919. Serial No. 342,137.

To all whom it may concern:

Be it known that I, JAMES F. SMITH, a citizen of the United States, and a resident of the city of St. Louis and State of Missouri, have invented a new and useful Improvement in Talking Machines, of which the following is a specification.

This invention relates to talking machines and has for its principal objects to provide means for adjusting the weight of the overhanging portion of the tone arm with relation to the sound record whereby the desired pressure of the stylus on the sound record may be obtained. Another object is to provide a flexible joint or connection between the tone arm and the main sound amplifying device that will permit universal movement of the tone arm without permitting escape of sound through the joint. A further object is to improve the tone quality by providing the tone chamber with a sound diffusing device. Further objects appear in connection with the following description of the invention.

The invention consists in the arrangements and combinations of parts hereinafter described and claimed.

In the accompanying drawing which forms part of this specification and wherein like symbols refer to like parts wherever they occur,

Fig. 1 is a central vertical section taken through a portion of a talking machine showing my invention applied thereto, the section being taken lengthwise of the sound conduit;

Fig. 2 is a vertical section crosswise of the sound conduit, the section being taken on the line 2-2 in Fig. 1;

Fig. 3 is a detail plan view showing the means for sliding the weight along the free end of the lever arm; and

Fig. 4 is a plan view of the slotted plate through which the weight actuating lever projects.

Referring to the drawings, 5 indicates the top of a talking machine cabinet, 6 the turn table on which the sound record 7 is mounted, 8 the tone chamber and 9 the main sound amplifier which leads from said chamber.

The tone arm 10 is arranged for easy lateral and vertical movement at its free end which has mounted thereon a sound box provided with two diaphragms. This sound box, which is of a well known make, is pro-

vided with three styluses 12, 13 and 14, the desired stylus being brought into engagement with the sound record by manual rotation of the sound box. The diamond stylus 12 is connected to one of the diaphragms of the sound box and is adapted to be used with a well known make of record having perpendicularly undulating record grooves. The styluses 13 and 14 are both connected to the other diaphragm of the sound box, the stylus 13 having a ball tip adapted for playing records having perpendicularly undulating record grooves and the stylus 14 having a sharp point for playing records having laterally undulating record grooves.

The tone arm support, which is shown and described, in my Patent No. 1,302,487, dated April 29, 1919, comprises an annular supporting bracket 15, which surrounds a circular opening 16 in the top of the cabinet, and is provided with a base flange adapted to be secured to the top of the cabinet in any desired manner. Mounted on oppositely disposed pivots 17 within the annular supporting bracket 15, so as to oscillate upon a horizontal axis and permit vertical movement of the free end of the tone arm, is a ring 18 which rotatably supports the enlarged end of the tone arm and permits the same to swing laterally. The tone arm is provided with an annular flange 19, and bearing balls 20 are arranged in the supporting ring 18 above and below the flange 19 to reduce the friction between the rotating tone arm and the supporting ring. A screw ring 21 is threaded into the supporting ring 18 to retain the annular flange 19 of the tone arm therein.

Communication between the tone arm 10 and the tone chamber 9 is established by means of a flexible tube 22. This tube is preferably made of sheet rubber or other flexible material. The upper end of the flexible tube 22 is secured to the supporting ring 18 by means of a spring clamping ring 23 and the lower end of the tube is sleeved over an annular projection on the upper end of the sound chamber 9. A coil spring 24 is positioned within the tube 22 to prevent the walls thereof from collapsing.

The upper portion of the tone chamber is provided with a sound diffusing device comprising a series of vertically spaced screens 25. These screens modify the sound by

eliminating harsh noises and act as tone purifiers.

A horizontally disposed lever arm 25 is fulcrumed in a bracket 26 secured to the 5 under side of the top of the cabinet. This lever arm is arranged parallel with the longitudinal axes of the oppositely disposed pivots 17 which pivotally support the tone arm supporting ring 18. The end of the 10 short arm of the lever 25 is connected to the front portion of the tone arm supporting ring 18 by means of a short link 27 whose upper end is pivoted between spaced lugs or ears 28 which project from the under side of the ring 18. The lower end of the 15 link 27 is pivoted to the end of the short arm of the lever 25. A weight 29 is slidably mounted on the free long arm of the lever 25 and serves to counterbalance the 20 overhanging portion of the tone arm and the sound box mounted thereon.

The pressure of the stylus on the sound record may be varied by sliding the weight 29 along the long arm of the lever 25 to 25 wards and away from the fulcrum of said lever. The movement of the weight along the lever arm is controlled from outside the cabinet by means of a hand lever 30 which is fulcrumed in a slot 31 cut in the top of the 30 cabinet. The upper end of the hand lever is provided with a finger button and the lower end is connected to the weight 29 by means of an extendible link comprising two sections 32 and 33. The section 32 of 35 the extendible link has one end secured to the lower end of the hand lever 30 and its other end laps one end of the other section 33 whose other end is pivoted to the weight 29. The lapped portions of the sections 32 40 and 33 of the extendible link are secured together by means of a pair of screws 34 which pass through a slot 35 in the section 32 and are threaded into the other section 33. This arrangement permits the link to 45 be lengthened or shortened and thus control the length of the sliding movement of the weight on the free end of the lever 25. A slotted plate 36 is fitted over the slot 31 in the top of the cabinet and the hand lever 50 30 which projects therethrough also projects through the slot in the plate 36. The slot 31 in the top of the cabinet is made wide enough to permit the hand lever to move lengthwise of its pivot, and the slot 55 36 in the plate 36 is provided with two notches 37 and 38 adapted to receive the hand lever and hold the same in either of its two adjusted positions.

With this arrangement, when it is desired 60 to play records which require a very slight pressure of the stylus thereon, the hand lever 30 is turned on its pivot and moved lengthwise thereof into the notch 37 in the plate 36. This action, by reason of the connection between the lower end of the hand

lever and the sliding weight, causes the weight to slide along the lever 25 in the direction of the bracket 26 in which the lever arm is pivoted. This causes the weight of the overhanging portion of the 70 tone arm and the sound box to be more evenly balanced and permits the stylus to bear lightly on the record. When it is desired to play records which require a heavy pressure of the stylus thereon, the action is 75 reversed, the hand lever being turned in the opposite direction and moved into the notch 38 in the plate 36. This causes the weight to be moved away from the fulcrum point of the lever 25 and permits the stylus to 80 bear more heavily on the record by reason of the increased weight of the tone arm and sound box. The pressure of the styluses 12, 13 and 14 on the sound record may be adjusted by shortening or lengthening the ex- 85 tendible link. This arrangement also permits the weight to be adjusted for use in connection with tone arms of different weights.

The foregoing arrangement is considered 90 only as an example and as the one best adapted to the tone arm shown in the drawing. Therefore, I do not wish to be limited to the precise details or arrangement of parts shown in the drawing. 95

What I claim is:

1. In a talking machine, the combination with a tone arm of a pivotally mounted supporting ring adapted to rotatably support said tone arm, a lever fulcrumed on 100 said machine and having one arm connected to said supporting ring, a weight movably mounted on the other arm of said lever, and means for shifting the weight along said second mentioned arm for counterbalancing the weight of said tone arm. 105

2. In a talking machine, the combination of a tone arm, a supporting ring mounted for oscillation upon a horizontal axis and adapted to rotatably support said tone arm, 110 a lever fulcrumed on said machine and arranged parallel with the axis of said supporting ring, one arm of said lever being connected to said supporting ring, a weight slidably mounted on the other arm of said 115 lever, and an operating lever connected to said weight for sliding the same along said second mentioned arm of said lever.

3. In a talking machine, the combination of a pivotally mounted tone arm adapted to 120 support a sound box at its free end, a lever fulcrumed on said machine and having one arm operatively connected to said tone arm, a weight slidably mounted on the other arm of said lever, an operating lever for sliding 125 said weight along said second mentioned arm of said lever, and an extendible means connecting said operating lever to said weight.

4. In a talking machine, the combination 130

- with a pivotally mounted tone arm of a lever fulcrumed on said machine and having one arm operatively connected to said tone arm, a weight slidably mounted on the other 5 arm of said lever, an operating lever for sliding said weight along said second mentioned arm of said lever, and an extendible link connecting said operating lever to said weight whereby the distance between said lever and said weight may be varied.
5. In a talking machine comprising a cabinet, the combination with a tone arm pivotally mounted on said cabinet of a fulcrumed lever disposed entirely within said 15 cabinet and having one arm operatively connected to said tone arm, a weight mounted on the other arm of said lever, and means extending outside of said cabinet
- for sliding said weight along said second mentioned arm of said lever for counter- 20 balancing the weight of said tone arm.
6. In a talking machine, the combination with a pivotally mounted tone arm of a lever fulcrumed on said machine, and having one arm operatively connected to said 25 tone arm, a weight mounted on the other arm of said lever, means for sliding said weight along said second mentioned arm of said lever for counterbalancing the weight of the tone arm, and means for vary- 30 ing the distance between said weight and the sliding means therefor.

Signed at St. Louis, Missouri, this 29th day of November, 1919.

JAMES F. SMITH.
